CRUSHING AND GRINDING MACHINE

Maude E. Meinhardt, Los Angeles, Calif.

Application April 17, 1939, Serial No. 268,226

1 Claim. (Cl. 83—53)

This invention relates to a crushing and grinding machine which, although more particularly intended for use as a rock crusher, may also be advantageously used to crush and grind a variety of other substances.

Among the objects of the invention are; to provide a pulverizer which will operate in a more efficient manner in respect to progressively reducing large chunks of rock, ore and the like to smaller pieces until, at last, they are finely pulverized, thus avoiding placing too great a strain upon the crushing elements at any stage of the reducing operation; to provide improved means for varying the amount of leverage exerted by the driving means upon the crushing elements operated thereby; and to improve upon crushing machinery by providing a more sturdy and durable construction and arrangement of parts for crushing and pulverizing the more obdurate class of materials.

Other objects, advantages and features of invention will hereinafter appear.

Referring in detail to the drawing.

Fig. 1 is a vertical mid section of the complete structure, taken on line 1—1 of Fig. 2.

Fig. 2 is an end elevation thereof.

Fig. 3 is a fragmental side elevation illustrating one of the rocker arms and showing the connection thereof with its operating means.

Referring in detail to the drawing, the box or casing structure is shown having a bottom or base 10, side walls 11 and end walls 12. Said base has a foot portion 13 extending from end to end thereof at each side in an alined underlying relation to each side wall 11, and extending from one of these foot portions to the other said base 10 has a delivery slot 14 of a downwardly widening character at each side of which is a downwardly directed lip 15.

The space between the side walls 11 is bridged by two inclined, stationary jaw members 17, which are identical in construction, each of said jaw members having a thickened base portion 18 having its bottom surface rounded to seat upon the upper surface of the base 10, said thickened portion 18 having a concave face 19 on its inner side, and on its outer side having a pair of recessed bosses 20 the recessed portions of which are engaged by the adjusting bolts 21 which extend into bores 22 provided through adjacent end walls 12. Adjusting nuts 21a are carried by said bolts. Said nuts each seat upon a concaved boss 21b projecting inwardly from the casing wall, and each bore 22 is of a considerably greater diameter than the bolt which

projects into it. This arrangement allows the bolt to swing a little, which is required for its proper adjustment. The upper part of each jaw 17 is thickened to form a head 23 having a shoulder 24 which rests upon the wall 12 and has a sliding movement in relation thereto when the jaw is adjusted. Each jaw head 23 has a concave face 25 corresponding in size and shape to the lower face 19.

Each jaw 17 is provided with a facing plate 26 having an arcuate lower portion 27 fittable within the jaw face 19 and an upper arcuate portion 28 fittable within the upper jaw concavity 25. An angular lower joint connection 30 and like upper joint connection 31 between each jaw and its facing plate aids in keeping each facing plate in its operative position. The opposite end portions of each stationary jaw 17 are also united to the facing plate by means of like joints 32 and 33. The mid-length portion of each facing plate 26 has crushing teeth 34 and a series of crushing teeth 35 is provided adjacent to each end of the straight portion of said facing plate, the teeth of each of said series diminishing in height as they approach the adjacent end of the plate.

A pair of upstanding slightly rockable crushing jaws 40 is mounted in the mid-length portion of the casing structure, said jaws being identical in construction and being furnished with identical crushing plates 41. Each of these jaws 40 has an arcuate thickened upper part 40a and somewhat similar thickened foot portion 40b. In order to mount said crushing plates 41 upon said jaws each jaw is furnished with the two lower angular joint connections 42 and 43 and like upper joint connections 44 and 45, each jaw 41 having a terminal projection directed toward its midlength to function as a part of an interlocking joint structure. Each plate 41 has central crushing teeth 46, and adjacent to each end of its straight face a like series of crushing teeth 47, which progressively diminish in height as they become more distant from the mid-length of the plate. The lower portion of the plate 41 has an arcuate part 48 and its upper portion has an arcuate part 49 to cooperate with the toothed arcuate parts of the stationary facing plates.

The toothed faces of the arcuate portions 48 and 49 of the facing plates 41 of the movable jaws define parts of a cylinder which has arcs 50 that have much shorter radii than the radii of the arcs of the concave face portions of the stationary facing plates with which they cooperate. Hence two upwardly widening feed intakes or throats 50 are provided at the lower part of the 55

structure, and also two downwardly widening feed discharge passages 51.

Like the crushing means, the driving means, next described, is duplicated at each side of the structure.

At the top of the mid-length of each side plate 11 is a hub portion 55 which supports a short bearing shaft 56. A pendant oscillatory bar 57 has a bore through its bearing portion 58 to receive the projecting outer end portion of said shaft 56. Above said shaft 56 said bar 57 has a head 59 furnished at each side in a spaced relation to its center with a bore 60 into which is rockingly fitted a stub shaft 61 rigidly carried by an upward extension 40x of the jaw 40 at that side of the structure. The pendant bar 57 extends down below its pivotal mounting a considerable distance and has its lower end portion pivotally fastened at 62 to an end of a connecting rod 63 which is driven by a crank 64 from a shaft 65 furnished with a driving pulley 67. At the same end of the casing each side wall 11 has a projecting portion 11x by which is supported a bearing 66 to sustain said shaft 65.

In order to provide for varying the distance between the fulcrum of each arm 57 and its connection with the connecting rod 63, the pivotal connection is made by means of a bearing block 70 adjustably supported by a screw 71 mounted between bosses 72 and 73 carried by said arm 57. This feature being of a conventional character, further description thereof is unnecessary.

The lower foot portion or arcuate part 40b of each central jaw member 40 is offset away from its mate, thereby affording a widened space 75 between these parts, and a horizontal I-beam 76 having its ends secured to the opposite side walls of the casing, extends through this space. At each side of the web of this beam is placed a roller bearing member 77 of a sufficient diameter 40 to fill up the width of the space between said web and the adjacent flat face of the foot portion 40b of the movable jaw 40 at its side of the machine. This construction provides anti-frictional bearing means for the lower portions 45 of the movable jaws, said jaws moving vertically as well as having a swinging motion. The outer faces of the movable jaw members 40 correspond throughout in contour to the inner faces of their facing plates 41 thus providing for a perfect 50 interfitting when these parts are assembled.

The casing base 10 is provided with openings 78 to discharge dirt. The side walls 11 have

openings 79 to afford access to the adjusting nuts 21n.

Owing to the undercut character of the shoulders of the connecting means 30 and 31 of each facing plate 26, each of said facing plates must 5 be moved in an edgewise manner into its attached relation to the body portion of the jaw 17 of which it forms a part, (and be detached in a similar manner) and this must be done before the assembled jaw members are placed within 10 the casing structure.

Owing to the fact that each of the movable jaws has a vertical, as well as a swinging movement, a pounding, as well as a rubbing action takes place in the throat portions 50 and in the 15 discharge passages 51, which causes a more nearly perfect pulverizing of the substances acted upon by the machine.

The movable jaw assembly having the facing plates 41, may be regarded, from the standpoint 20 of function, as a single jaw having a crushing surface at each side.

I claim:

In a crusher, an open topped casing having a floor and side walls rectangularly arranged as 25 viewed in plan, the side walls of said casing extending farther up than its end walls, two inclined stationary oppositely disposed jaw members each of an elongated plate-like character and having a lower end portion resting upon the 30 floor of said casing adjacent to its central portion, the upper portion of each said stationary jaws having a head of a generally right angled contour in its lower outer portion with a rounded groove in its corner portion, the grooved part 35 thus provided resting loosely upon a shoulder afforded therefor by the upper edge of the end wall at its end of the casing, the inner surface of said head being concave thereacross superjacent to said groove, extensible and contractible 40 means positioned between said jaw's lower end portion and the adjacent end wall of the casing to vary the inclination of such jaw, a lining member for each jaw having a convex outer portion fitting into the aforesaid concave surface of said 45 head to aid in keeping in place, movable means occupying the space between said lining members of said stationary jaws to cooperate with them in the performance of a crushing operation, and outlet means to discharge the crushed 50 materials.

MAUDE E. MEINHARDT.
